UNITED STATES PATENT OFFICE

HARRY E. KATZENMOYER, OF ROSEDALE, PENNSYLVANIA, ASSIGNOR TO FISHER HOSIERY CO. INC., OF READING, PENNSYLVANIA, A CORPORATION OF PENNSYLVANIA

METHOD AND APPARATUS FOR CUTTING OFF FLOAT THREADS

Application filed April 16, 1930. Serial No. 444,675.

This invention relates to an improved method and apparatus for cutting off the ends of float threads which are usually left in the production of reinforced circular knit stockings.

These reinforcing threads, as a rule, are in the high spliced heel and the reinforced sole, and such extra threads are introduced during the knitting for only a portion of each circular course, and as they span the stocking tube, the portions of the float threads which extend across the interior of the stocking must be cut away as close to the fabric as possible, to neatly finish the hose.

The primary purpose of the present invention is to provide a novel method and apparatus for not only expeditiously cutting off the loose ends of the float threads close to the fabric without damaging the latter, but which allows a number of operators stationed about a rotary table or turret, to successively place the stockings on suitable supports, to clip the floating ends of the thread, and to then remove the stockings from the forms.

Another object is to furnish a system of this character, including a suction apparatus positioned above the form table, and having suction arms which are arranged directly above the clipper stations, so that the ends of the float threads are not only raised to facilitate the cutting of the same, but such ends, as soon as they are severed, are immediately removed by the suction apparatus.

A further object is to provide a novel stocking form comprising spaced rods which hold a stocking tout, and yet allow the fabric to yield under the pressure of the clipper, whereby excess pressure exerted on the clipper by an operator, will be prevented from damaging the hose.

Another object is to provide a stocking support of oscillatable type, to allow the operator, after clipping the floating ends at one side of the stocking, to turn the latter to a position so that the floating ends at the opposite sides of the stocking may be clipped.

A further object is to furnish each clipper used, with a novel guard which not only tends to lift and guide the ends of the float threads, but acts to maintain the teeth of the

clipper out of contact with the fabric of the hose.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a plan view of the form table of my improved apparatus, and showing how eight operators may be placed around the same in such manner that four of these operators may put stockings on and remove them from the forms, while four other operators are clipping the ends of the float threads from such stockings.

Fig. 2 is an enlarged vertical sectional view taken on the line 2-2 of Fig. 4, and showing one of the stocking forms or supports.

Fig. 3 is a top plan view of the same.

Fig. 4 is a transverse vertical sectional view of the form on the line 4-4 of Fig. 2.

Fig. 5 is a diametrical sectional view of the form table shown in Fig. 1, but with the suction apparatus arranged above the same, and having its suction arms positioned directly above the forms when the latter arrive at the clipper operator stations.

Fig. 6 is a top plan view of the suction device.

Fig. 7 is a side elevation of a power operated clipper, forming part of the invention.

Fig. 8 is a top plan view of the same.

Fig. 9 is a top plan view of the clipper guard.

Fig. 10 is a perspective view of one of the forms with a stocking arranged thereon, and showing the operator about to clip the floating ends from the stocking at one side of the latter.

Fig. 11 is a similar view of the form and stocking, after the movable portion of the form has been turned to bring the float threads at the other side of the stocking, uppermost.

Referring to the drawings, 12 indicates a carrier, table or turret mounted to rotate

about an axle 18. Such a table may be turned by hand, or may be intermittently rotated step by step by any suitable means, not shown.

5 Posts 14 have their lower ends rigidly secured to the table, and are preferably equally spaced about the peripheral portion of the table. In the example illustrated, there are eight of these posts to accommodate eight 10 operators who are positioned at stations about the table. For instance, at the four points 15, four operators will be stationed to place unfinished stockings on the skeleton forms 16, and to remove the stockings from 15 the forms, while at the intermediate stations 17, four operators will be located to clip the ends of the float threads from the stocking.

As best shown in Figs. 2 to 4 inclusive, 20 each form is mounted at the upper end of one of the posts, and such a form may consist of a collar 18 having a horizontal axis, and provided at its inner end with an inwardly extending flange 19 which is overlapped by the edge of a circular disk 20 that is secured to the post by any suitable means, such as screws 21. This construction allows the collar 18 to turn about the disk, and for the purpose of limiting such turning 25 to an oscillating motion, a stop pin 22, that is rigidly connected to the collar 18, projects through an arc-shaped slot 23, which is concentrically arranged in the stationary disk 20.

Bosses 24 which are preferably spaced 120 30 degrees apart on the collar, are rigidly connected to projecting rods 25 that form a triangular assembly, and have their outer ends curved and merging into one another as at 26. These merging ends form a nose for 35 the support to receive the toe portion of a stocking which is turned inside out when it is mounted on the support; and one of the arms has a hook 27 to accommodate a special toe on certain types of stockings. This arm 40 also has an offset or depressed portion 28 to receive the heel portion of the reversed stocking, and when the form is in the position shown in Figs. 1 and 2, it will be manifest 45 that the offset portion 28 will function as an indicator to guide an operator in placing a stocking on the form in such a way that the ends of the float threads will project in opposite directions from the form, and will be positioned between the arms 25, as clearly 50 shown in Fig. 10.

At this point, let us assume that at the start of the operation, the operators at stations 15 place four stockings on the forms 16 at these locations, in the manner indicated in 60 Fig. 10. Now the table will be given a one-eighth rotation, so as to bring these four stockings to the clipper operator stations 17.

Each of the clipper operators, as shown in 65 Fig. 10, will now turn his stocking bearing form until the pin 22 reaches the lower end

of the slot 23, and this will cause the ends 29 of the float threads to arrive in the position shown in Fig. 10, in which they are located on a horizontally disposed portion 30 of the tubular stocking 31 and between the opposite 70 side bars of the form. Now, when the operator moves the clipper 32 over the horizontal portion 30 of the stocking, the threads 29 will be clipped, and as the portion 30 is stretched between the opposite side bars of the form, it will be obvious that this portion 30 can yield under the pressure of the clipper, so that the threads will be severed close to the fabric without damaging the latter. At the same time, the suction device, 75 described hereinafter, will act to cause the ends 29 to stand up, and will suck the severed ends away as soon as these ends are cut from the fabric.

80 After the clipper operator has removed the ends 29, he will turn the form 16 to bring the ends 33 at the opposite side of the stocking, uppermost, and in this operation, the pin 22 will move to the upper end of the slot 23. Now, it will be seen that the ends 33 85 project upwardly from a horizontally disposed portion 34 of the stocking, which is stretched between the side bars of the form which are uppermost at this time. Here also, as the operator moves the clipper 32 over the 90 horizontally disposed portion 34 of the stocking, the stocking will yield under the pressure of the clipper, and the ends 33 will be cut off close to the fabric without damaging 95 the latter.

100 While the clipper operators at the stations 17 are clipping the four stockings, the operators at the four stations 15 are placing four more stockings on four of the forms 16, whereby as soon as the clipper operators 105 finish with the first four stockings, the table is ready to be turned to bring four new stockings into position to have the ends of the float threads severed. At the time the clipper operators are ready to start on the 110 second four stockings, the operators at stations 15 will remove the clipped stockings, and place four unclipped stockings on the forms, and this operation will be repeated 115 throughout the working period.

120 Referring now to Fig. 5, it will be observed that a suction chamber 35 is positioned above the table 12, and may be connected to any suitable vacuum pump by means not shown. Extending downwardly from this chamber, 125 are four pipes 36 arranged at ninety degrees relatively to one another, and each carrying at its lower end, a suction arm 37, which arms are opposite the clipper operator stations 17, and are positioned directly above the path of movement of the forms 16. As suction is continuously exerted in the arms 37, it will be apparent that whenever a form carrying an unclipped stocking comes beneath one of these arms, and the form is turned in the 130

position shown in either of Figs. 10 or 11, the loose thread ends will be sucked upwardly, so that they will be upstanding when they are clipped, and the severed ends 5 will be withdrawn through the arms 37, pipes 36 and chamber 35. In this way, the accumulation of débris is prevented from interfering with the work of the operators.

The loose ends of the float threads may be 10 severed by any suitable means. For instance, hand clippers may be used, but to facilitate the operation, I prefer to employ power operated clippers of the type shown in Figs. 7 and 8. However, I provide such a power 15 clipper 38 with a special guard 39 of the type shown in Fig. 9. This guard is provided with apertures 40 which may receive screws that are employed to adjustably secure the guard to the under side of the clipper. If shims 20 are used with such screws, obviously, the guard may be spaced different distances away from the bottom of the clipper, so as to raise or lower the knives of the clipper to permit cutting more or less of the loose ends of the 25 float threads away from the stockings.

The guard is provided with forwardly projecting spaced fingers 41 having upturned ends 42 to prevent these ends from digging into the fabric as the clipper passes over the 30 latter. As the fingers are spaced apart, they form a throat or cavity 43, into which the threads move as the clipper passes along the stocking, and any threads which tend to adhere to the stocking and lie upon the same, 35 will be initially lifted by these guard fingers, so that they may be readily handled by the suction apparatus.

It will be understood that while the float 40 threads, during knitting of the stocking, ordinarily extend approximately diametrically across the cylinder from edge to edge of the reenforced area, the drawings indicate them as intermediately severed. Such severing is 45 a preliminary step performed before the beginning of my aforesaid clipping operation and may be accomplished by an automatic attachment to the knitting machine operating during the knitting of the stocking; or may subsequently be done by hand or on a 50 separate cutting device.

While I have disclosed a system in which the forms are arranged on a rotatable table, it will be obvious that the same system may be employed in any environment where the 55 forms travel in an endless path, it only being essential to have a clipper operator between each two operators who place the unclipped hose on the forms and remove the clipped hose from the forms.

60 The terms and expressions employed herein are used as terms of description and not of limitation, and there is no intention in the use of such terms and expressions, of excluding any equivalents of the features shown and described, or portions thereof, but it is rec-

ognized that various structural and other modifications are possible within the scope of the invention claimed.

What I claim and desire to secure by Letters Patent is:

1. A method of removing loose ends of 70 float threads from circular knit hosiery, consisting in intermediately severing the float threads, stretching a stocking inside out on a form with the ends of the float threads projecting outwardly in opposite directions, and then clipping said loose ends from the fabric.

2. A method of removing the loose ends 75 of float threads from circular knit hose inside out, comprising arranging the hose on a skeleton form with a portion of the stocking stretched between opposite supports and the ends of the loose threads projecting outwardly from this portion of the stocking, and then clipping the loose ends from the stretched portion of the stocking.

3. A method of removing the loose ends 80 of float threads from stockings, comprising yieldingly supporting a reversed stocking in such manner that the loose ends project outwardly from a stretched portion of the stocking, and then severing the loose ends from the yieldingly supported portion of the stocking.

4. A method of removing the loose ends 85 of float threads from hosiery, consisting in turning a stocking inside out on a skeleton frame, so as to yieldingly support the portions of the hose from which the loose ends project, and then clipping the loose ends from stocking by 90 passing a clipper over the yieldingly supported portions of the stocking.

5. A method of removing the loose ends 95 of float threads from hosiery, comprising turning a stocking inside out and supporting the same on a skeleton form on which the portions of the stocking from which the loose ends project are yieldingly supported, then cutting one line of said loose ends from the fabric, then turning the form to bring the other line of loose threads in a particular location, and finally severing the last mentioned line of loose ends from the fabric.

6. A method of removing the loose ends 100 of float threads from circular knit hose, comprising placing a triangular skeleton form into a stocking which has been turned inside out, positioning the stocking on the form in such manner that the portions of the stocking from which the lines of loose threads project are yieldingly supported, then passing a clipper over one of the yieldingly supported portions of the stocking and thereby clipping 105 one line of said loose ends from the stocking, then turning the form to bring the other line of loose threads uppermost, and finally passing a clipper over the portion of the stocking from which the last mentioned line of loose threads projects, and thereby sever- 110

ing the last mentioned line of loose threads from the stocking.

7. An apparatus of the class described, comprising a movable carrier, a number of stocking supports mounted on said carrier, a suction chamber, and suction arms communicating with said chamber and arranged in close proximity to the path of movement of said supports.

19 8. An apparatus of the character described, comprising a rotatable table, a series of spaced stocking supports carried by the table, a suction chamber, and suction arms radially arranged with respect to the table, and positioned in close proximity to the path of movement of said forms.

20 9. A method for use in removing the loose ends of float threads from tubular stockings or the like, which comprises relatively moving a series of skeleton stocking supporting forms past a series of operator stations, removing a previously cut stocking and yieldingly stretching an uncut stocking inside out on each form passing alternate operator stations, and at the stations between said alternate stations severing said float threads by passing a clipper over said stretched fabrics.

25 10. A method for use in removing the loose ends of float threads for tubular stockings or the like, which comprises relatively moving a series of skeleton stocking supporting forms past a series of operator stations, removing a previously cut stocking and yieldingly stretching an uncut stocking inside out on each form passing alternate operator stations, at the stations between said alternate stations severing said float threads by passing a clipper over said stretched fabrics, and at each such severing 40 station passing said form in close proximity beneath a suction chamber extension to lift said float threads and carry them away when severed.

45 11. An apparatus of the character described, comprising an intermittently rotatable table, a series of spaced brackets secured thereto, a rotatable support mounted on each bracket, a skeleton frame stocking support of substantially triangular cross section carried by each support, and radially fixed suction arms positioned in close proximity to the path of travel of said forms and arranged to simultaneously overlie every alternate form when said table is at rest.

50 55 In testimony whereof I affix my signature.
HARRY E. KATZENMOYER.
